(57) **CLAIM**

The ornamental design for a valve for a nozzle as shown and described.

DESCRIPTION

FIG. 1 is a top perspective view of a valve for a nozzle in accordance with the present invention;

FIG. 2 is a top plan view of the valve for a nozzle of FIG. 1;

FIG. 3 is a front elevational view of the valve for a nozzle of FIG. 1 where the rear, right side, and left side elevational views are identical to the front elevational view; and,

FIG. 4 is a bottom plan view of the valve for a nozzle of FIG. 1.
